UNITED STATES PATENT OFFICE.

MORIS F. KOCH, OF NEW YORK, N. Y.

DESIGN FOR A FRAME OF WEIGHING-SCALE.

SPECIFICATION forming part of Design No. 15,393, dated September 9, 1884.

Application filed May 2, 1884. Term of patent 14 years.

To all whom it may concern:

Be it known that I, MORIS F. KOCH, of New York, in the county and State of New York, have invented a new and original Design for 5 the Frame of a Weighing-Scale, of which the following is a description.

In the accompanying photograph, Figure 1 represents an end elevation of the frame of the scale. Fig. 2 is a perspective view of the 10 same.

This invention relates to a new, useful, and original shape or configuration of the frame A of a weighing scale.

I claim—

The design for the frame A of a scale, substantially as shown. 5

MORIS F. KOCH.
